UNITED STATES PATENT OFFICE

JOSEPH DAMELIO, OF YOUNGSTOWN, OHIO

DESIGN FOR A FLOWERPOT HOLDER

Application filed April 23, 1930. Serial No. 35,365. Term of patent 14 years.

To all whom it may concern:

Be it known that JOSEPH DAMELIO, a citizen of the United States of America, residing at Youngstown, in the county of Mahoning and State of Ohio, has invented a new, original, and ornamental Design for Flowerpot Holder, of which the following is a specification, reference being had to the accompanying drawing, forming part thereof.

The figure is a perspective view of the flower pot holder.

I claim:

The ornamental design for a flower pot holder as shown.

In testimony whereof I affix my signature.

JOSEPH DAMELIO.
